(57) **CLAIM**

The ornamental design for the enclosure for electronic device, as shown and described.

DESCRIPTION

FIG. 1 is a front, right and top perspective view of the enclosure;

FIG. 2 shows a front plan view of the enclosure;

FIG. 3 shows a rear plan view of enclosure;

FIG. 4 shows a right side elevation view of the enclosure, the left side elevation view being a mirror image thereof;

FIG. 5 shows a bottom elevation view of the enclosure, the top elevation view being a mirror image thereof;

FIG. 6 shows a side elevation view with unclaimed vents shown in broken lines;

FIG. 7 shows an elevation view of the top or bottom of the enclosure with the unclaimed battery compartment door shown in broken lines;

FIG. 8 shows a bottom elevation view of the enclosure with the unclaimed button and protruding front shown in broken lines;

FIG. 9 shows a rear, left, and bottom perspective view of the enclosure with the unclaimed US-style plug shown in broken lines;

FIG. 10 shows a rear, left, and bottom perspective view of the enclosure with the unclaimed European-style plug shown in broken lines;

FIG. 11 shows a rear, left, and bottom perspective view of the enclosure with an unclaimed mounting socket shown in broken lines;

FIG. 12 shows a rear, left, and bottom perspective view of the enclosure with another unclaimed mounting socket shown in broken lines;

FIG. 13 shows a front right and top perspective view of the enclosure with unclaimed indicators shown in broken lines;

FIG. 14 shows a front right and top perspective view of the enclosure with an unclaimed camera shown in broken lines;

FIG. 15 shows a front right and top perspective view of the enclosure with an unclaimed motion sensor shown in broken lines;

FIG. 16 shows a front right and top perspective view of the enclosure with an unclaimed network bridge shown in broken lines;

FIG. 17 shows a front right and top perspective view of the enclosure with an unclaimed light dimmer module shown in broken lines; and,

FIG. 18 shows a front right and top perspective view of the enclosure with an unclaimed nightlight feature shown in broken lines.

The broken lines (where present) in all Figs. illustrate portions of the enclosure for electronic device that form no part of the claimed design. The dash-dot lines are included to represent the boundaries of the claimed design and form no part of the claimed design.
